STOCKING

Herbert M. Suess, Elkins Park, Pa.

Application April 22, 1949, Serial No. 2,202

Term of patent 14 years

(Cl. D47—7)

To all whom it may concern:

Be it known that I, Herbert M. Suess, a citizen of the United States, residing in Elkins Park, in the county of Montgomery and State of Pennsylvania, have invented a new, original, and ornamental Design for a Stocking, of which the following is a specification, reference being had to the accompanying drawing, forming part thereof.

Fig. 1 is a fragmentary perspective view of a stocking, showing my new design;

Fig. 2 is a side elevational view on a reduced scale of the stocking shown in Fig. 1 as it appears on the leg; and

Fig. 3 is an enlarged side elevational view of the stocking shown in Fig. 2.

I claim:

The ornamental design for a stocking, as shown.

HERBERT M. SUESS.
